UNITED STATES PATENT OFFICE.

ALFRED H. SMITH, OF CHAPPAQUA, AND EDWARD G. MINER, OF ROCHESTER, NEW YORK; SAID MINER ASSIGNOR TO PFLAUDLER COMPANY, OF ROCHESTER, NEW YORK, A CORPORATION OF NEW YORK.

SECTIONAL REFRIGERATOR CAR.

Application filed October 3, 1922, Serial No. 592,144, and in Canada August 17, 1922.

The object of our invention is to provide a plurality of containers adapted to be secured to and removed from a railroad car or other vehicle without impairing the security and stability of the remaining containers on the car or vehicle, each container being so constructed that it may be filled at the point of loading, lifted by a crane to the car, transported thereon, and at destination lifted to a motor truck or delivered to a bottling house where the container may be emptied into small receptacles for delivery, thus providing a more economical handling of liquid.

It is fairly well settled now that there is a demand for some form of bulk transportation for milk to displace the present small unit system.

In the majority of cases, the large milk dealers gather their supply from different stations along the route, and at none of these stations is there sufficient milk to fill one of the big cars. Containers are placed at receiving stations in the country and filled, and are then picked up by trains and loaded into place on the car quickly and delivered to the motor truck or milk companies in the large cities.

According to our invention, these containers will be lifted from the car at the terminal and placed on the milk companies' trucks for movement to their Pasteurizing and distributing plants, thus eliminating the handling of a large number of small units as is now the case.

A further object of our invention is to provide these shipping tanks or receptacles with a suitable covering of insulation to substantially maintain a given temperature for the milk while in the receptacle.

While we have specially mentioned milk, it will, of course, be understood that fruit juices, high grade dyes and the like may be shipped in these receptacles.

Our invention consists in a shipping container, having top, bottom and side walls, a suitable insulation between said walls, and a receptacle fixedly secured within said container, an inlet and an outlet for said receptacle, ports in the walls of said container registering the said inlet and outlet, and with this and other objects in view, our invention consists of the parts and combina-

tion of parts, as will be hereinafter more fully set forth.

In the drawings.

Figure 1 is a side elevation of a railroad car on which are arranged a series of the refrigerator units,

Fig. 2 is a top plan view of a portion of Figure 1, a portion of the car being broken away,

Fig. 3 is a side elevation of one of the units partly in section, and

Fig. 4 is an end elevation of one of the units, partly in section.

The reference numeral 1 designates the railroad car or other carrier of suitable construction, and 2 designates the detachable refrigerator units arranged transversely thereon, which are adapted to receive milk, and other liquid for transportation in bulk.

The car is preferably provided with suitable side and end walls, 3, 4 and 5, respectively, the side walls being provided with vertically disposed guides 6. The units are provided with locking members 7 which are adapted to engage the guides 6 on the car, whereby the units are locked against shifting and rocking on the car while in transit. These locking members are beveled in two directions toward their bottom edge, whereby the units are centered on the car as they are lowered onto the car by reason of the bevels engaging the abutments and guides, as will be readily understood from the drawings.

By reason of the guides and side walls, one or more of the units may be removed from the car without impairing the stability or safety of the remaining units, and besides which, as will be pointed out, the outlet of each unit is back of an abutment, such as the side wall, when on the carrier, therefore, the outlet contents of the unit cannot be manipulated, thereby preventing unauthorized removal of the contents of the unit.

Each container is provided with wall braces 8 and 8^a, a lifting plate 9, secured to the wall and said braces, and a hook or loop 10 adapted to be engaged by a crane whereby the units may be readily lifted from or onto the carrier. The brace 8^a is attached to the bottom sill of the container.

While the walls of the unit may be of

any suitable construction, we prefer to form them on a suitable framing of timbers 11 connected at the bottom by sills 12 and at the top by carlines 13, which sills and carlines are provided with saddles or seats adapted to fit snugly that portion of the wall of the tank 13' which comes in contact therewith; the tank being securely held in position against shifting in the unit by means 10 of the straps 14, the ends of which are securely fastened to the underframe of the unit by means of the shackle 15.

We will refer to the unit as a container and to the tank as a receptacle in the claims.

15 The unit, or container, is provided with a man hole at the top, which is lined on the inside by means of two of the carlines 15', and a superposed wooden lining 16 which has an undercut 17 under which is secured 20 a suitable insulation 18, such for instance, as hair felt, and the lower edge of which rests on the top edge of the plate 19 which is welded to the tank or receptacle 13'. The outer face of the lining piece 16 is beveled 25 to provide a wedging seat for the plug 20 for the manhole, said plug being provided with lifting handles 21. 22 is a cover of suitable construction for the manhole, hinged at 23 and having a suitable hasp lock or 30 other connection 24.

The walls of the unit or container are double walls having a suitable insulation, such as cork, packed between them, our preference being to make the outer face of the 35 walls of any suitable insulating material.

The tank or receptacle 13' may be made of any suitable material so long as it is liquid proof, but we prefer to make it of metal, and it may be provided with a noncorrosive 40 lining as indicated at 25.

This tank or receptacle is provided with an inlet 26 in alignment with the manhole of the container or unit, the inlet having a suitable upstanding collar with an outwardly 45 extending flange 27, there being a suitable filling 28 such for instance as "Sargo", on top of the tank sloping from the collar 26 toward the plate 19, to provide drainage from the collar of any liquid which may 50 splash outside of the collar, which liquid is drained off by means of the drain pipe 29 leading outside of the unit. There is a suitable insulation 30 between the tank and drain pipe as shown in Fig. 4, a portion only of 55 the insulation being seen in Fig. 4, inasmuch as the strap 14 obscured the remainder.

The inlet of the tank or receptacle is provided with a cover 31 which is secured thereto by means of the bolts 32, the cover being 60 provided with lifting handles 33.

The tank or receptacle 13' is provided at the bottom with a screw threaded outlet 34, to which a hose, or other suitable conveyor 65 may be attached, whereby the contents of the tank may be removed. It will be noted that

a suitable plate 35 is positioned at this end of the tank around the opening of the outlet 34, and with a suitable flashing 36, constitutes a housing, which is formed between the end wall of the unit and the tank, which 70 housing is closed at its open end by means of the insulated door or cover 37, in the end wall of the unit.

By reason of such housing the spaces between the end wall and the outlet is kept 75 free from dirt, and other foreign matter, and, at the same time the space in the housing provides insulation.

Of course, it will be understood that the outlet 34 is provided with a cover 38. This 80 outlet is protected by the door 37, which is provided with a suitable lock 40 and hinges 39.

While we have shown a specified construction for the purpose of illustrating our invention, it will be understood that changes 85 may be made therein, and a different construction selected within the scope of the appended claims.

As is well known, milk and the like, is now 90 handled in metallic cans, and it is necessary to handle each can individually a number of times between the producer and the consumer, besides which these cans are easily damaged, and frequently become lost, which 95 increases the cost of the milk to the consumer. A plurality of cans of the capacity of one of our improved receptacles or tanks would take up a larger amount of space on a railroad car than one of the tanks. 100

What we claim is:

1. A shipping container having spaced top, bottom, end and side walls, suitable insulation between said spaced walls, a man hole in one of said walls and a cover for the 105 same, a receptacle fixedly secured within said container, an inlet for said receptacle registering with said man hole, an outlet for said receptacle, a port in a wall of the container registering with said outlet, and a cover for the inlet port of the receptacle. 110

2. A shipping container having spaced top, bottom, end and side walls, insulation between said walls, ports in the top and end walls of the container, insulated covers for 115 said ports, means for locking said covers in said ports, a receptacle mounted within said container and provided with a man hole inlet and with an outlet, a cover for the man hole of the receptacle and means to lock it in place, a cover for the outlet, and means to lock said man hole cover in closed position, suitable means to control the outlet of said receptacle, and straps positioned over the receptacle and anchored to the container, and saddle blocks secured to the container and resting snugly against the top wall of the container. 120

3. A shipping container having spaced top, bottom, end and side walls, insulation 125

between said walls, ports in the top and end walls of the container, insulated blocks for said ports, a man hole for said container, a man hole cover, means for locking said cover on said man hole, a receptacle mounted within said container, and provided with a man hole inlet, and with an outlet, a cover for the man hole inlet of the receptacle, and means to lock said covers in closed position, 10 suitable means to control the outlet of said receptacle, and straps positioned over the receptacle and anchored to the container and saddle blocks secured to the container and resting snugly against the top wall of the receptacle, and lifting ears secured near each corner of the container and locking elements on each end of the container.

4. A shipping container having spaced top, bottom, end and side walls, insulation 20 between said walls, inlet and outlet ports in the top and end walls of the container, in-

sulated blocks for said ports, means for locking said blocks in the inlet and outlet and a receptacle mounted within said container and provided with an inlet and an outlet, a 25 cover for the inlet of the receptacle, and means to lock it in place, suitable means to control the outlet of said receptacle, and straps positioned over the receptacle and anchored to the container, and saddle blocks 30 secured to the container and resting snugly against the top wall of the receptacle, and lifting ears secured near each corner of the container, and locking means on the exterior face of two diametrically opposite walls of 35 the container for locking said container on a vehicle.

In testimony whereof we affix our signatures.

ALFRED H. SMITH.
EDWARD G. MINER.
